UNITED STATES PATENT OFFICE.

MARCUS C. HOPKINS, OF NEW YORK, N. Y., ASSIGNOR, BY MESNE ASSIGNMENTS, TO LEKTOPHONE CORPORATION, OF NEW YORK, N. Y., A CORPORATION OF DELAWARE.

SOUND-REGENERATING MACHINE.

1,271,528.

Specification of Letters Patent. Patented July 2, 1918.

Application filed December 24, 1913, Serial No. 808,577. Renewed March 22, 1918. Serial No. 224,049.

To all whom it may concern:

Be it known that I, MARCUS C. HOPKINS, a citizen of the United States, residing in the borough of Manhattan, city, county, and State of New York, have invented certain new and useful Improvements in Sound-Regenerating Machines; and I do hereby declare the following to be a full, clear, and exact description of the invention, such as will enable others skilled in the art to which it appertains to make and use the same.

My invention relates to improvements in sound regenerating machines.

15 It relates particularly to sound regenerating machines of the "direct" type in which the sound waves are regenerated by a tympanum without the employment of amplification devices, such as horns or trumpets.

20 My present invention is an improvement on the invention described and illustrated in an application filed by me July 14, 1913, and having Serial Number 778,826.

The object of my present invention is to 25 provide a simple, efficient, and easily operated mechanism, the parts of which may be cheaply made and assembled.

A further object of my invention is to provide a mechanism in which the style exerts 30 a relatively powerful leverage in vibrating the tympanum, thereby greatly reducing the wear on the record, and, by reason of the small relative movement of the tympanum, eliminating distortions which would result 35 from movements of greater amplitude; the tympanum being, however, of such area that the relatively small range of movement produces sound waves of large volume and carrying power constituting, without amplification by a sound box, horn or the like, a 40 substantial regeneration of the original recorded sound waves.

The aforesaid and other novel features of my invention are hereinafter fully described and claimed.

In the accompanying drawings which illustrate the preferred form of my invention,

Figure 1 is a view partly in plan and 50 partly in horizontal section of my improved machine.

Fig. 2 is a view in side elevation and partly broken away.

Fig. 3 is an enlarged fragmental horizontal 55 sectional view of the rigid supporting

bar and parts connected therewith, taken on the line 3—3 of Fig. 5.

Fig. 4 is a cross section on the line 4—4 of Fig. 3.

Fig. 5 is an end view of what is shown in 60 Fig. 3, looking at the end having the style holder.

Fig. 6 is a longitudinal vertical sectional view, a portion of the transmission member and rigid bar being broken away, taken on 65 the line 6—6 of Fig. 5.

Fig. 7 is a horizontal sectional view through the rigid bar, showing a modification, some of the parts being broken away.

Figs. 8 and 9 are respectively side and end 70 views of collars 17 and 19, the former being shown partially in section.

Similar reference characters designate similar parts in the different views.

1 designates the cabinet in which is mounted 75 a suitable motor, not shown, which is adapted to drive a flat top revoluble record table 2, upon which is adapted to be placed a disk record 3.

The cabinet at one end is provided with a 80 raised portion 4 which provides a compartment in which is disposed vertically a tympanum 5, preferably provided with a central conical portion 6, to the apex of which is secured a cap 7, to which is connected the transmission mechanism, which will be hereinafter described.

The outer edges of the tympanum 5 are 85 clamped between two ring members 8 and 9, the latter being supported by radial rods 10, 90 the inner ends of which are fastened to a collar 11, which is secured by a set screw 12, Fig. 1, to a rigid horizontal cylindrical bar 13, which is supported by a universal joint 95 upon a bracket 14, which is secured to a portion of the cabinet frame.

The universal joint just referred to comprises a ring member 15, which is pivoted by means of two oppositely disposed trunnion screws 16 to a collar 17 in which the 100 bar 13 is rotatable on its axis.

For limiting the rotation of the bar 13, it has secured to it at one end of the collar 17, a collar 19, shown in Fig. 9, which is provided with two notches 19', in the end adjacent to the collar 17, said notches being adapted to receive a bolt 18 mounted in a hole in the adjacent end of the collar 17, and normally forced outwardly by a spring 18' contained in said hole, see Fig. 8. 110

The ring member 15 at its lower side is provided with a vertical stem 20 pivoted in a socket in the bracket 14.

When the bar 13 is rotated on its axis, the bolt 18, by means of its pressure will retain the bar in the position to which it is rotated. The notches 19' have inclined bottoms and at one set of ends terminate abruptly, whereby the bolt will readily enter the notches, and will readily move from one notch toward the other, but the abrupt ends of the notches will limit the rotation of the bar in each direction.

Insulation 21 of suitable material, such as soft rubber, may be provided between the bracket 14 and the part of the cabinet frame to which it is secured.

To enable the tympanum 5 to freely vibrate in unconfined air, and to provide paths 20 to the surrounding atmosphere, the walls of the upstanding portion 4 of the cabinet may be provided with a sufficient number of openings, and if desired, for protecting the parts these openings may be provided with grille work 22.

A cover 23, Fig. 2, may be hinged to the forward upper edge of the upstanding portion 4 of the cabinet, for the purpose of closing the forward end of the portion 4 30 and for covering the record table 2.

I will now describe the tensioned transmission mechanism.

Referring particularly to Figs. 4 to 6, it will be noted that the bar 13 is provided therethrough with a longitudinal hole 24, through which extends a transmission member comprising, preferably, a light rod 25, which extends through a notch in a vertical lever 26, which is pivoted on two fulcra 27, mounted in the bar 13, at the adjacent end thereof, and having knife edges resting in recesses provided in the lever 26. This lever carries a style holder 28 having a set screw 29 for securing thereto, at an inclination to the axis of the lever 26, a style 30. It will be noted that the axis of the lever which carries the style holder 28 is disposed substantially perpendicular to the record, when the style 30 is in the operative position on the record. This disposition of the axis permits the style to travel transversely in a plane, instead of swinging in a curve relative to the surface of the record, and effects a more accurate following of the undulations at the sides of the record groove than could be otherwise obtained.

The end of the rod 25, on the outer side of the lever 26 bears against a member 31, to which it is secured by means of a screw 32, which extends through a hole provided in the member 31. The latter member is provided on its inner side with knife edges 33, which bear upon the outer side of the lever 26 at one side of the axis thereof.

Secured to said lever 26, and extending to

the other side of the axis of said lever, is a flat spring 34, which is provided with a hole through which extends a screw 35, which is mounted in a screw-threaded hole in the adjacent end of the bar 13, and which has 70 mounted upon it, preferably, two nuts 35' which bear respectively against the spring 34 and the bar 13, and which serve to tightly clamp the screw 35 to the spring 34 and to the bar 13, thereby preventing distortions 75 due to looseness of these parts.

Similarly mounted in the opposite end of the bar 13, is a screw 36, which bears against a flat spring 37 secured to a lever 38, which is mounted on knife edge members 39 secured in the adjacent end of the bar 13. Nuts 37' on the screw 36 hold said screw tightly to the bar 13 and to the spring 37.

The transmission member 25 extends through a notch in the lever 38, and is secured tightly to the inner side of a member 40 by means of a connecting member 42, which extends through the member 40, against the outer side of which it bears, and is provided with a threaded end which is 80 fitted in a threaded hole in the adjacent end of the member 25.

The member 40 is provided with knife edges 41 which are mounted in recesses provided therefor in the adjacent side of the 85 lever 38.

The other end of the connecting member 42 bears against the inner side of the cap 7, to which it is secured by a screw 43, which extends through a central hole provided in 100 the cap 7, and fits in a threaded hole in member 42.

The cap 7 is provided with an externally screw threaded central tubular projection on which is fitted a clamping member 44, between which and the cap 7 the tympanum 5 105 is clamped.

The screws 35 and 36 hold the levers 26 and 38 against the adjacent knife edges, and also, by swinging the similar ends of the levers in opposite directions, impart a tension to the transmission member 25 in the direction of its vibratory movement. As the springs 34 and 37 counterbalance each other, the levers 26 and 38 are free to be 115 oscillated on their supporting knife edges.

It will be noted that the tympanum supporting rings 8 and 9 are mounted very closely to the universal joint on which the bar 13 swings. This permits the style, in 120 traversing the record, to swing the tympanum and its support as on a pivot, and without undue wear on the record, the style being located far from and the tympanum support near to the pivotal support of the 125 bar 13.

It will also be noted that the distance of the style 30 from the axis of the lever 26 is much greater than the distance between the axis and the knife edge bearings 33 of the 130

member 31, to which the transmission member 25 is secured. By means of this construction, the length of vibration of the tympanum is much less than that of the style and 5 the tympanum thus offers little resistance to the movement of the style, thus greatly reducing the wear of the record. To compensate for the small movement of the tympanum, it has a large area, preferably exceeding 10 nine inches in diameter, and is, preferably, provided centrally with a rigid portion of relatively large area, whereby it is enabled to move a large body of air, so as to obtain sound waves of large volume and 15 great carrying power.

The tensioned transmission is longitudinally rigid, so as to permit the tympanum to accurately respond to the movements of the style. The bar 13 is of such ponderous proportions and weight that it will not respond to the rapid mechanical vibrations of the style holder, and such molecular vibrations as are transmitted to it, are transmitted to the tympanum without distortion.

25 While the levers 26 and 38 and the rod 25 are under tension, this tension is not extended to the tympanum, but the tympanum, preferably, is left untensioned so as to freely move. The tympanum, being conical, will 30 be very rigid and will, therefore, be moved bodily, instead of having merely a local disturbance set up therein, as would be the case if it were flat and of a yielding nature.

In the operation of the invention, the bar 35 13, which serves as a handle, and for which purpose it is provided at its forward end with a cap 45, having a lateral finger piece 46, Fig. 1, is swung on the universal joint to the proper position for playing. The bar 40 40 may be rotated on its axis, by grasping the finger piece 46, to a position in which a style may be removed from or inserted into the style holder 28. The cap 45 is provided at its forward end with a hole through which 45 the style holder 28 projects.

In the form of my invention shown in Fig. 7, the construction is the same as that shown in Figs. 4 to 6, excepting that for the springs 34 and 37, which swing the levers 26 50 and 38, there is provided a spring wire 47, which extends through the hole 24 in the bar 13, and which has its ends secured by screws 50 to knife edge members 49, which bears respectively upon the outer sides of 55 the levers 26' and 38', which correspond in function and location to the levers 26 and 38 of the other form of my invention. The levers 26' and 38' are mounted respectively upon knife edge bearings 27 and 39, which 60 are secured in opposite ends of the bar 13. As in the other form of my invention, the transmission member 25 is connected by a connecting member 42 to the tympanum, and has a longitudinal tension imparted to it by 65 the levers 26' and 38' through the interme-

diacy of the spring wire 47, which is provided with a convolution 48, which permits the wire 47 to exert a spring tension.

In the form of my invention shown in Fig. 7, the spring wire 47 also holds the levers 70 firmly seated upon their fulcrum.

When the stylus 30 is swung by the record, its vibrations will be transmitted mechanically by the levers 26' and 38', the wire 47, rod 25 and connecting member 42, to 75 the cap 7, and from the cap to the tympanum.

While, for convenience of illustration, I have shown the relative distances between the axis and stylus, and between the axis and 80 the knife edges supporting the transmission member 25, as being about three to one, it is desirable that this proportion should be largely increased, and that the transmission member 25 should be connected to the levers 85 26 and 38 very close to their axes. I have found that, in direct sound regeneration from a record, the very best results are obtained by employing a tympanum, having an area sufficient to move a large amount of air, 90 so as to produce the desired volume and carrying power, when moved through a range much less than the range of movement of the stylus. Inasmuch as the movement of the stylus itself is relatively small, it will be 95 understood that the transmission connecting the stylus and the tympanum, in view of the much less movement of the tympanum, must be longitudinally very rigid and at the same time easily oscillated. These conditions are 100 realized in the structure of this invention, the direct connection of the tympanum with the tensioned transmission member, and the spring pressed levers effecting the longitudinal rigidity; and the employment of knife 105 edge bearings for the joints effecting the required freedom of oscillation. The positioning of the knife edge supports for the tensioned transmission member very close to the axis of the style holder relative to the 110 much greater distance between said axis and the point of the style, effects the desired leverage for the style upon the tympanum and imparts to the tympanum the very slight movement desired, the limited movement of 115 the tympanum being compensated for by its large area and rigidity.

I do not limit my invention to the structures described and illustrated, as many modifications, within the scope of the 120 appended claims, may be made without departing from the spirit of my invention.

Having thus described my invention, what I claim and desire to secure by Letters Patent, is:—

1. In a sound regenerating machine, a sounding tympanum, a stylus-holder and a transmission member connecting the tympanum and the stylus-holder, and through which vibrations of the stylus produced by 130

the groove of a record tablet are transmitted to the tympanum, in combination with yielding tensioning means connected to the transmission member between the tympanum and 5 the stylus holder and vibrating therewith, and serving to impart continuous yielding lengthwise tension thereto.

2. In a sound regenerating machine, a rigid support, two levers pivoted thereon, a 10 transmission member carried by said levers, a style holder carried by one of said levers, a tympanum connected to said transmission member, and two springs respectively operating upon said levers to effect a tension in 15 said transmission member.

3. In a sound regenerating machine, a rigid support carrying two knife edges, a vibration transmission member, two levers carrying said member and respectively pivoted on said knife edges, a style holder carried by one of said levers, a tympanum connected with said transmission member, and yielding means operating upon said levers to effect a tension in said transmission member 20 and to retain said levers seated on said knife edges.

4. In a sound regenerating machine, a rigid support, two levers pivoted thereon, a transmission member carried by said levers, a 30 style holder carried by one of said levers, a tympanum connected to said transmission member, two springs secured respectively to said levers, and means operating upon said springs for forcing said levers to positions 35 in which a tension will be imparted to said transmission member.

5. In a sound regenerating machine, a bar having fulcra at its opposite ends, two levers respectively pivoted on said fulcra, a style 40 holder carried by one lever, a transmission member carried by said levers, a tympanum connected with said transmission member, and two springs respectively operating upon said levers to impart a tension to said transmission member.

6. In a sound regenerating machine, a bar, two levers pivoted thereto at opposite ends thereof, a style holder carried by one of said levers, a transmission member carried by 50 said levers, a tympanum connected with said transmission member, two springs respectively carried by said levers, and means carried by said bar and operating upon said springs to force said levers to positions in which a tension will be imparted to said transmission member.

7. In a sound regenerating machine, a bar having a longitudinal hole therethrough and provided at opposite ends with fulcra, two 60 levers respectively pivoted on said fulcra, a style holder carried by one of said levers, a transmission member extending through said hole and carried by said levers, a tympanum connected with said transmission member, and yielding tensioning means operating 65

upon said levers for imparting a continuous lengthwise tension to said transmission member.

8. In a sound regenerating machine, a bar having a hole longitudinally therethrough, two levers pivoted to opposite ends thereof, a style holder carried by one of said levers, a transmission member carried by said levers and extending through said hole, a tympanum connected with said transmission member, and resilient means operating upon said levers for effecting a tension in said transmission member. 70

9. In a sound regenerating machine, a bar having a longitudinal hole therethrough, two levers pivoted to opposite ends thereof, a style holder carried by one of said levers, a transmission member carried by said levers and extending through said hole, a tympanum connected with said transmission member, two springs carried respectively by said levers, and means by which said springs operate on said levers to impart a tension to said transmission member. 75

10. In a sound regenerating machine, a vibration transmission support, a style holder and a tympanum support carried thereby, and means for pivotally supporting said transmission support at a point closely adjacent to said tympanum support and remote from said style holder, said means providing for the rotation of said transmission support upon its longitudinal axis. 80

11. In a sound regenerating machine, a vibration transmission support, a style holder and a tympanum support carried thereby, and a universal bearing pivotally supporting said transmission support at a point closely adjacent to said tympanum support and relatively remote from said style holder, said bearing providing for the rotation of said transmission support upon its longitudinal axis. 85

12. In a sound regenerating machine, a vibration transmission support, a style holder and a tympanum support carried thereby, and a bearing pivotally supporting said transmission support at a point closely adjacent to said tympanum support and relatively remote from said style holder, said bearing comprising two pivoted members, one pivoted on the other, the transmission support being rotatable about its longitudinal axis on one of said members, the axes of said members being at right angles to each other. 90

13. In a machine for directly regenerating sound from a record of the same, a vibratile conical tympanum of large area rigidly supported at its periphery and freely exposed to unconfined air, a stylus-holder, a vibration transmission member connected to the tympanum, and a pivoted lever con- 125

130

necting the stylus-holder with the transmission member; the connection of said lever with the transmission member being considerably closer to the pivot than is the record-engaging end of a stylus supported in the holder, whereby the movements of the tympanum are of substantially less amplitude than the movements of the record-engaging end of the stylus, the tympanum being 5 of sufficient area to impart to the surrounding free air, when the tympanum is so vibrated, sound waves substantially corresponding in intensity to the recorded sound waves.

14. In a machine for directly regenerating sound from a record of the same, a vibratile conical tympanum of large area rigidly supported at its periphery and freely exposed to unconfined air, a stylus-holder, a 10 vibration transmission member connected to the tympanum, means for tensioning the transmission member independent of the tympanum in the direction of its vibration, and a pivoted lever connecting the stylus-holder with the transmission member, the connection of the lever with the transmission member being considerably closer to the pivot than is the record-engaging end of a stylus supported in the holder, whereby 15 the movements of the tympanum are of substantially less amplitude than the movements of the record-engaging end of the stylus, the tympanum being of sufficient area to impart to the surrounding free air, when the tympanum is so vibrated, sound waves substantially corresponding in intensity to the recorded sound waves.

15. In a machine for directly regenerating sound from a record of the same, a vibratile conical tympanum of large area rigidly supported at its periphery and freely exposed to unconfined air, a stylus-holder, a 20 vibration transmission member connected to the tympanum, means for tensioning the transmission member independent of the tympanum in the direction of its vibration, and a pivoted lever connecting the stylus-holder with the transmission member, the connection of the lever with the transmission member being considerably closer to the pivot than is the record-engaging end of a stylus supported in the holder, whereby 25 the movements of the tympanum are of substantially less amplitude than the movements of the record-engaging end of the stylus, the tympanum being of sufficient area to impart to the surrounding free air, when the tympanum is so vibrated, sound waves substantially corresponding in intensity to the recorded sound waves.

16. In a machine for directly regenerating sound, a vibratile conical tympanum of large area rigidly supported at its periphery and freely exposed to unconfined air, a sound-vibrated element, and a single transmission member between said tympanum and said element maintained under tension and arranged to impart to the tympanum vibrations which are relatively much shorter than the vibrations of the record end of the style, the tympanum having a vibratile area sufficiently large to effect, without amplification, sound waves of large volume and 30 carrying power.

16. In a sound regenerating machine, a support, two oscillatable members, knife edge bearings on said support respectively supporting said members, knife edge bearings mounted respectively on said members, a transmission member mounted on the last named bearings and adapted to be actuated by a style, a tympanum connected with said transmission member, and means for holding said oscillatable and transmission members tightly against the bearings which respectively support them.

17. In a sound regenerating machine, a support, two oscillatable members, knife edge bearings mounted on said support and respectively supporting said members, a tensioned transmission member adapted to be vibrated by a style, and knife edge bearings respectively mounted on said oscillatable members and supporting said transmission member.

18. In a machine for directly regenerating sound, a vibratile conical tympanum of large area rigidly supported at its periphery and freely exposed to unconfined air, a sound-vibrated element, and a single transmission member between said tympanum and said element maintained under tension and arranged to impart to the tympanum vibrations which are relatively much shorter than the vibrations imparted to said element.

In testimony whereof I affix my signature, in presence of two witnesses.

MARCUS C. HOPKINS.
